CLAIM

I claim the ornamental design for a bouffant hair bonnet, as shown and described.

DESCRIPTION

FIG. 1 is a top perspective view thereof;

FIG. 2 is a bottom perspective view thereof;

FIG. 3 is a front elevation view thereof;

FIG. 4 is a rear elevation view thereof;

FIG. 5 is side elevation view thereof;

FIG. 6 is a top plan view thereof; and,

FIG. 7 is a bottom plan view of my new design.

The broken lines shown in FIGS. 2 and 7 define the bounds of the claimed design and form no part of the claim thereof.

The broken lines shown on the headband portion of the bonnet form no part of the claimed design.
